Primary Examiner — Darlington Ly

(74) Attorney, Agent, or Firm — John J. Connors;
Connors & Assoc. pc(57) **CLAIM**

The ornamental design for a vehicle cab, as shown and described.

DESCRIPTION

FIG. 1 is a perspective view of the vehicle cab according to my design;

FIG. 2 is a left side elevation view thereof;

FIG. 3 is a front elevation view thereof;

FIG. 4 is a top plan view thereof; and,

FIG. 5 is a right side elevation view thereof.

The broken line showing a vehicle is for the purpose of illustrating environmental structure and forms no part of the claimed design.
